HAIR WAVING APPARATUS

John B. Copenhefer, Louisville, Ky.

Application September 10, 1936, Serial No. 100,138

19 Claims. (Cl. 132—38)

This invention relates to the art of waving hair and has particular application to apparatus by means of which the user may arrange her own coiffure. Heretofore, in apparatus of this general nature difficulty has been experienced in forming a satisfactory wave due to the complexity of the apparatus used. Since the user customarily employs a mirror in waving her own hair and since the mirror image is reversed, any apparatus of a complicated nature requires skillful use and entails a slow waving operation. Moreover, in most apparatus of this type it is extremely difficult to remove the apparatus from the hair after the wave is formed without disarranging the wave to a greater or less extent.

The present invention provides a solution to these disadvantages and offers a means by which a user may wave her own hair in a satisfactory and distinct manner in accordance with any style which she may wish to employ. It is to be expressly understood, however, that the invention is not intended to be limited to use solely in this manner, but on the contrary may well be employed by professional hair dressers in waving the hair of their clients.

One object of the invention is the provision of a simple and efficient apparatus by which a user may wave her own hair;

Another object is the provision of means for removing the apparatus from the hair without disarranging the wave;

Another object is the provision of means for varying the depth of the wave and for insuring a uniform waving of all hair held by the apparatus;

A further object is the provision of hair waving apparatus which may be securely held in any direction so that a wave may be formed in accordance with any style selected;

A further object is the provision of means which is light in weight and sturdy in construction and which may be cleaned easily after use;

Other objects and advantages will become more apparent as the description proceeds when considered in connection with the accompanying drawing in which;

Figure 1 is a plan view of the comb element,

Figure 2 is an elevation of the comb element,

Figure 3 is a section taken along line 3—3 of

Figure 2,

Figure 4 is a plan view of the wave forming element,

Figure 5 is an elevation of the wave forming element,

Figure 6 is a section taken on line 6—6 of Figure 5,

Figure 7 is a view showing the assembled apparatus at the conclusion of the wave forming operation,

Figure 8 is a view showing the assembled apparatus in ready position prior to the wave forming operation, and

Figure 9 is a sectional view taken on line 9—9 of Figure 8.

As will be noted from the drawing, the apparatus comprises essentially two elements which cooperate to produce the desired waving effect. In Figures 1 to 3 the first of these elements is shown and for convenience may be termed a "comb element". One form which may be used comprises spaced side walls 1 and 2 forming a channel structure within which the wave forming element is movably journaled. In order to conform to the general contour of the head so that an efficient waving of the hair may result, the apparatus is designed with a concave inner surface and with a convex outer surface.

The upstanding side walls 1 and 2 of the comb element are joined to depending walls 3 and 4 by means of bearing ledges 5 and 6 providing secure bearing surfaces for the movable waving element later to be described. Formed in the lower faces of each of walls 3 and 4 is a plurality of comb-like teeth 7, providing the means for holding the hair to be waved. It is contemplated that the teeth on wall 3 will be duplicates of the teeth on wall 4 and will be correspondingly spaced. For convenience of manufacture, especially when apparatus molded by dies is to be used, it is intended that the axis of all teeth will be formed on parallel lines as shown. Even though these parallel axes of the several teeth result in teeth of different length, it is found that the resulting advantage of lifting the comb element along a single direction without disarranging the formed wave more than offsets any disadvantage in non-uniformity of the several comb teeth.

Side walls 1 and 2 of the comb element are rigidly held in their proper relation by spacing members 8 and 9 located adjacent the ends of these walls and by a housing 10 positioned intermediate the ends of the comb element.

Referring now to Figures 4 to 6 wherein the wave forming element is shown, it will be noted that the structure employs the identical concave inner surface and convex outer surface used upon the comb element with which it cooperates. An elongated "backbone" member 20 is provided

along its upper surfaces with longitudinal ribs 21 and 22 adapted to fit within walls 1 and 2 of the comb element and to have a relatively close fit against the lower portion of housing 10. 5 Bearing surfaces 25 and 26 of the wave forming member similarly coincide with the shape of bearing ledges 5 and 6 of the comb member with the result that when the apparatus is assembled there can be no improper rocking motion between 10 the respective parts. It will be noted in this connection that ample bearing surface for heavy duty is provided by ledges 5 and 6 and that bearing surfaces 25 and 26 extend close to the lower side walls 3 and 4 thus preventing the 15 trapping of any loose hair between the bearing ledges and the bearing surfaces. As a result of this construction severe strains, such as may be occasioned by the so called "tight waving", may be placed upon the apparatus without resulting 20 in breakage of the same.

Along the lower concave surface of member 20 a plurality of wave forming teeth 27 are positioned. In general, these teeth are preferably constructed in parallel relation and are inclined 25 at a reverse angle from that employed by the teeth upon the comb element. As will be apparent, however, the precise shape of the teeth upon either element, the inclination of such teeth or the number and size thereof may be widely 30 varied without departing from the scope or intent of the invention and it is to be understood that the invention is not to be limited solely to the form herein shown.

Since the wave forming member may move an 35 appreciable distance within the comb element and since certain of the end teeth on that comb element may tend to hold strands of hair, an extension member 28 is provided as shown and forms a continuation of backbone member 20. By 40 means of this construction the surfaces 25 and 26 are extended so that when the comb element is disengaged from the wave forming element any hair trapped by any teeth 7 will be positively pushed from those teeth by the edges of surfaces 45 25 and 26. As a consequence, no portion of the waved hair is disarranged and a more desirable effect results.

In order to assemble and secure together the 50 elements as hereinabove disclosed, parallel up-standing supports 30 and 31 are constructed upon the wave forming member. These supports serve a dual function in that they provide an assembly means for the apparatus and at the same time provide a means for the actuation of the structure. Disposed transversely of the supports 30 and 31 at 55 a predetermined height are removable rods 32 and 33 adapted to ride upon the upper edges of walls 1 and 2 when the apparatus is assembled for the waving operation. As shown in Figure 9, 60 bearing surfaces 25 and 26 are flush against bearing ledges 5 and 6 in this position and due to the same curvature being used upon both the comb and wave forming elements, no rocking movement either longitudinally or transversely 65 can result. At the same time any stresses imposed upon the structure through the resistance of the hair is distributed over the large bearing area.

At the top of housing 10 a conveniently shaped 70 thumb seat 34 is provided and as will be noted, support 30 extends above rod 32 a substantial distance. Moreover, an open channel between walls 1 and 2 and above the slot 29 in member 20 is provided and as a result a convenient means for holding and operating the apparatus is placed at 75 the user's disposal. Due to this feature the device

may be handled with either hand and may be used upon any portion of the hair without fear of dropping the structure or of operating the same improperly.

While an apparatus embodying only the structure thus far described may be employed with a certain measure of success in the waving of hair, it is found that certain disadvantages are present. Primarily, the chief problem is the disengagement of such apparatus from the hair after the 10 wave is formed. Hair caught between teeth 7 and teeth 27 after being formed into a wave tends to hang upon those teeth and in order to loosen the usual apparatus from the hair a short reverse movement of the wave forming element must take 15 place. This movement tends to destroy the formed wave and requires considerable skill and practice upon the part of the operator.

In order to avoid this disadvantage the present invention provides means for releasing the apparatus from the waved hair without disarranging the wave. Formed into side walls 1 and 2 of the comb element are slots 40 and 41 into which rods 32 and 33 are adapted to fit when the wave is completely formed. These slots are formed at the 20 same angle as the axis of teeth 7 on the comb member for a purpose later to become apparent.

Resilient means of any suitable nature such as a compression spring 42 positioned within recess 43 of housing 10 provides a reliable means for 30 lifting the comb member from the hair at the conclusion of the waving operation. As will be obvious, the angle of slots 40 and 41 determines the direction in which the comb member will be 35 lifted and since the least disarrangement will result when the teeth 7 of the comb member are moved parallel to the axis of those teeth, those slots accordingly are made parallel to the axis of the teeth.

Due to relative displacement between the comb 40 and wave forming members during the waving operation and during this lifting operation, it is found desirable to provide a housing member such as a hollow cup 44 for retaining the exposed 45 lower end of spring 42. This cup is of such dimensions as to remain journaled in recess 43 of housing 10 even in the raised position of the comb member, as shown in Figure 7. The smooth bottom of cup 44 rests securely in the slot 29 of the wave forming member at all times and permits an 50 efficient relative movement between the two members even while the spring is under compression. By means of this construction no torsional 55 stresses are placed upon the spring and the spring is effective to lift the comb member at the instant rods 32 and 33 enter slots 40 and 41.

One manner of operating the apparatus as thus described may take the following sequence. With the hair prepared for waving the user forces the comb and wave forming members together compressing spring 42 and forcing rods 32 and 33 from slots 40 and 41. The wave forming member is then moved to a ready position shown in Figure 8 with rods 32 and 33 sliding along the top edges of walls 1 and 2. For convenience, a 65 marked scale S is provided along one edge of the comb member and is adapted to cooperate with rod 32 on the wave forming member.

The extent to which the wave forming member is moved determines the degree of wave resulting 70 and such a scale provides a ready means of assuring the precise amount of waving desired.

With the apparatus thus secured in a ready position and being held between the support 30 and thumb seat 34 by one hand the user places 75

the apparatus on that portion of the hair in which a wave is desired. The teeth 7 and 27 (as shown in Figure 8) nestle deep into the hair and as support 39 is moved toward housing 10 by 5 the pressure of the fingers the hair is guided between teeth 7 on each side of the comb member and is pulled into a curved path by the movement of teeth 27. When the desired degree of waving is obtained rods 32 and 33 fall into slots 40 and 10 41 and spring 42 effects the raising of the comb member from the hair. The waved hair, however, still remains in contact with teeth 27 which are unaffected by the lifting of the comb member. The operator then lifts the apparatus gently from 15 the hair and teeth 27 are removed without disturbing the wave. As will be apparent, the device is intended to be reset after the formation of each wave since at the completion of the waving movement (Figure 7) the comb member and the 20 wave forming member are separated through the action of spring 42. When the device is reset for subsequent use spring 42 is manually compressed and pins 32 and 33 are cammed outwardly in slots 40 and 41 and are moved to the 25 left (Figure 8) along the top of walls 1 and 2 a given distance depending upon the nature of the wave desired. In this way supports 30 and 31 and cup 44 housing spring 42 are lifted above the strands of hair which are to be waved. Subsequent waves at different locations and directions or in a continuation of the same wave may be 30 made to suit the user's fancy by a repetition of this procedure until the coiffure is completed. An additional advantage resulting from the construction disclosed above lies in the fact that the entire apparatus is operable at all times above the hair being waved. No members extending into and under the hair and lifting the same outwardly into the waving means are required. 35 In certain prior constructions of such nature the removal of the apparatus from the hair without disarranging the wave entailed both a slow and expert operation on the part of the user whereas the present device may be used rapidly and successfully even by unskilled operators.

In thus disclosing the invention it will be noted that certain features such as the parallel teeth, the inclination of slots 40 and 41 and the parallel construction of supports 30 and 31 have been 50 mentioned. While a satisfactory adaptation of the invention may well be made without these specific features and is so intended to be covered by this disclosure, certain practical reasons suggest the use of these features. It is contemplated that the apparatus will be constructed of a light and strong material such as bakelite, tennite or similar plastic and will be molded into shape. Any satisfactory apparatus must have smooth 55 surfaces for engaging with the hair and for this reason parallel lines along which a mold may be drawn will give the best results and will avoid the formation of fins or obstructions upon the molded article.

The device as thus constructed may be easily 60 cleaned after use since in its disengaged position the several parts are readily accessible for cleaning or inspection.

Having thus described the invention, it is apparent that numerous changes in design and construction of the same may be employed without departing from the essentials thereof. With the intention, therefore, of including such changes in the above disclosure as will occur to the person skilled in the art,

I claim:

1. Hair waving apparatus comprising in combination, an elongated channel member having comb-like teeth disposed along the sides thereof and inclined in one direction, a wave forming member journalled in the channel member and having teeth inclined in another direction, means holding the members together for sliding engagement during the wave forming operation and means for automatically disengaging the members 10 when the wave is formed.

2. In a hair waving apparatus, comb-like means holding the hair in place, wave forming means journalled in the comb means, and means automatically disengaging the comb means from 15 the wave forming means at the completion of the wave forming operation, whereby the apparatus may be removed from the hair without disarranging the wave.

3. In a hair waving apparatus having a comb-like means for holding the hair and a comb-like means for forming the wave automatic, means for lifting the comb-like means from the hair whereby the apparatus may be removed without 20 disarranging the wave.

4. In a hair waving apparatus, a comb-like means for guiding the hair and having teeth inclined at a uniform angle in one direction, wave-forming means having teeth inclined at a uniform angle in another direction and means for 30 lifting the comb means from the hair at the same angle as the angle of the comb teeth whereby the apparatus may be removed without disarranging the wave.

5. Hair waving apparatus comprising in combination, a member having spaced inclined teeth disposed along the sides thereof, a member journalled within the first member and movable for a variable distance therein whereby a wave of 35 variable size may be formed, said member having teeth disposed in an opposite direction, means securing the two members together and spring means effective to force the members apart in a predetermined location.

6. In a structure of the character described, spaced comb-like means for guiding the hair to be waved, wave forming means movable within the comb-like means and having edges disposed in close proximity to the comb-like means and means for separating the comb-like means and the wave forming means after the wave is formed 50 whereby hair held by the comb-like means will be pushed therefrom by the edges of the wave forming means when the waving operation is completed.

7. In a structure of the character described, spaced comb-like means for guiding the hair to be waved, wave forming means including a rearwardly extending member movable within the comb-like means and having edges disposed in close proximity to the comb-like means and means for separating the comb-like means and the wave forming means after the wave is formed whereby hair held by the comb-like means 60 will be pushed therefrom by the edges of the wave forming means and rearwardly extending member when the waving operation is completed.

8. Hair waving apparatus comprising a comb member having bearing surfaces on its lower face, a wave forming member movable along the comb member and having bearing surfaces on its upper face and means holding the members together for contact along the bearing surfaces during the waving operation whereby stresses 70 75

imposed through operation of the apparatus may be distributed along the bearing surfaces.

9. Hair waving apparatus comprising a comb member having bearing surfaces on its lower face, a wave forming member having bearing surfaces on its upper face, means holding the members together for contact along the bearing surfaces during the waving operation and means for automatically disengaging the comb member from the wave forming member at the completion of the waving operation whereby the apparatus may be lifted from the hair without disarranging the wave and may be readily cleaned after use.

10. In a hair waving apparatus, a comb member having depending teeth inclined at an angle and engaging the hair, and automatic means for lifting the comb upwardly from the hair along the same angle as the axis of the teeth whereby the apparatus may be removed without disarranging the hair.

11. In an apparatus of the character described, a comb member having inclined teeth formed on parallel axes and a wave forming member cooperating with the comb member for engaging the hair and having inclined teeth formed on other parallel axes whereby smooth parallel surfaces may be provided for engagement of the teeth with the hair in order to render the apparatus easily removable from the hair.

12. A hair waving device operable above the hair to be waved to provide for removal of the device without disarranging the formed wave comprising, a comb member having depending teeth inclined in one direction serving to hold the strands of hair from above said hair, a wave-forming member journalled in the comb member for relative movement therewith and having depending teeth inclined in an opposed direction serving to engage the strands of hair from above said hair, and means holding the respective members in cooperating position during the waving operation whereby hair may be waved by the action of the respective opposed teeth and may remain in the waved condition when the device is lifted upwardly from the hair.

13. A hair waving device operable above the hair to be waved to provide for removal of the device without disarranging the formed wave comprising, a comb member having parallel depending teeth inclined in one direction serving to hold the strands of hair from above said hair, a wave-forming member journalled in the comb member for relative movement therewith and having parallel depending teeth inclined in an opposed direction serving to engage the strands of hair from above said hair, and means holding the respective members in cooperating position during the waving operation whereby hair may be waved by the action of the respective opposed teeth and may remain in the waved condition when the device is lifted upwardly from the hair along the axis of the parallel teeth.

14. In a hair waving apparatus, a comb member having spaced walls providing a guide means adjacent their upper edges, inclined depending comb teeth formed in the lower edges of said

walls, a wave forming member movably journalled between the walls and having depending teeth oppositely inclined from the comb teeth and transverse guide rods rigidly affixed to the wave forming member adapted to move along the 5 guide means on the walls in order to hold the respective members in operable position during the engagement of their oppositely inclined teeth with the hair.

15. In a hair waving apparatus, a comb member having spaced walls providing a guide means, a wave forming member movably journalled between the spaced walls and guide rods rigidly affixed to the wave forming member adapted to move along the guide means on the walls in 10 order to hold the respective members in cooperating 15 position during the wave forming operation.

16. In a hair waving device, a comb member having spaced walls providing a guide means adjacent their upper edges, inclined depending 20 comb teeth formed in the lower edges of said walls, guide channels cut into the upper sides of said walls, a wave forming member having depending teeth oppositely inclined from the comb teeth and adapted to fit movably between the 25 spaced sides of the comb member, and transverse guide rods affixed to the wave forming member adapted to move along the guide means in the spaced walls to secure the members in cooperating 30 relation during the waving operation and to move into the guide channels at the end of the waving operation in order to separate the said members for ready removal of the device from the hair.

17. In a hair waving device, a comb member having spaced walls providing a guide means 35 adjacent their upper edges, parallel inclined depending comb teeth formed in the lower edges of said walls, parallel guide channels cut into the upper sides of said walls on the same axis as the comb teeth, a wave forming member having 40 parallel depending teeth oppositely inclined from the comb teeth and adapted to fit movably between the spaced sides of the comb member, and transverse guide rods affixed to the wave forming member adapted to move along the guide 45 means in the spaced walls to secure the members in cooperating relation during the waving operation and to move into the guide channels at the end of the waving operation in order to separate the said members for ready removal of the device 50 from the hair.

18. In a device of the character described in claim 16, resilient means interposed between the comb member and wave forming member and adapted to separate the members automatically 55 when the guide rods move into the guide channels on the comb member walls.

19. In a device of the character described in claim 17, resilient means interposed between the comb member and wave forming member and adapted to separate the members automatically 60 by raising the comb member upwardly along the axis of its depending teeth when the guide rods move into the guide channels on the comb member walls.

JOHN B. COPENHEFER.
